UNITED STATES PATENT OFFICE.

SOREN C. ROCKMAN, OF PHILADELPHIA, PENNSYLVANIA.

STEAM-TURBINE.

1,157,727.

Specification of Letters Patent. Patented Oct. 26, 1915.

Application filed November 11, 1913. Serial No. 800,354.

To all whom it may concern:

Be it known that I, SOREN C. ROCKMAN, a citizen of the United States, residing at Philadelphia, in the county of Philadelphia and State of Pennsylvania, have invented certain new and useful Improvements in Steam-Turbines, of which the following is a specification.

My invention relates to steam turbines.

10 My object is to construct a rugged and simple turbine of fewer parts, more compact and of less weight and first cost and more economical in steam and operation than at present obtained.

15 In the drawing, Figure 1 represents a half outside elevation and a half sectional elevation. Fig. 2 is a section at *a* of the blading shown in Fig. 1.

Similar numerals refer to similar parts 20 throughout the drawing.

In the drawing, 1 is a valve for admitting steam through nozzle 2, to impulse wheel 3 which is mounted on an enlarged portion on shaft 4 which also carries a disk 25 5. The shaft 4 has a collar 6 and a screw threaded portion so that the disk 5 and the wheel 3 with separator 7 between may by means of nut 8 be forced up against the collar 6. The shaft 4 has shoulders against 30 bearings 9 and 9' so as to prevent end motions. The bearings are preferably intact with the covers which are bolted to the flanges of casings 12 and 12', which incloses the disk or wheel 5, and the wheel 3, respectively.

The cover 10 is provided with stationary blades or vanes 13 and the wall 14 of the casing 12 is also provided with stationary blades or vanes 13. The disk 5 is provided 40 with moving blades or vanes 15 extending out both sides and matches and coöperates with blades 13 in the casing 12. The disk is provided with passages as 16 so that the steam from the impulse wheel may also pass 45 to and through the outer wreaths of blading as well as through the inner wreaths of blading. The disk and the casing with the moving and stationary blades respectively forms a reaction turbine receiving steam, 50 that has passed one or more stages, one being shown, of the turbine provided with impulse wheels and in which the steam has given up energy, the residue of which is further abstracted in the reaction bladed

part of the turbine having exhaust outlet 55 part 17 leading to the atmosphere or into the condenser.

The disk 5 into which the blades are secured preferably by dovetailing may be made in one casting or forging or it may be 60 made up of rolled steel plates riveted together and connected to the shaft by means of hubs. The moving blades will then be stamped and ground and provided with shoulders and riveted to the steel plates 65 which have holes with nicks or serrations into which the riveted portions are driven so as to prevent turning of the blades.

The disk is shown straight, but it may be made thick in the center and converging 70 outward uniformly or in steps. The wall 14, particularly opposite the blading 16 on the impulse wheel 3 and opposite the inlet for the steam, may be insulated by asbestos or the non-conducting medium *g* by a thin 75 plate ring *f*, secured to the wall 14, so as to prevent radiation of the heat of the steam leaving the impulse wheel, which has a higher pressure and temperature than the low pressure steam in the casing 12, through 80 the wall 14. The wall 14 extends inwardly to where the bladed part of the low pressure reaction blading begins.

The working wheel 3 as shown represents a driving element consisting of an impulse 85 wheel with two pressure stages, however, one or more impulse wheels without pressure stages may be placed in casing 12' if desired.

The wall 10' of cover 10 may have an inlet 25' near the center provided with a valve for the entrance of steam for increasing (boosting), the power of the turbine.

The moving blades may have notches 20 for inserting strong wires or bands 21 which 95 extend around over all blades of the circle so as to form a strong construction, the wires 21 being wired or nicked over and soldered to the blades. The impulse wheel 3 may be reinforced and be provided with 100 reaction blades coöperating with stationary blades secured on wall 14, as shown at C.

The shaft 4 extends through bearing 9 and carries any well known coupling not shown for connection to an electric generator or a pump or for any machinery desired to operate. The shaft also passes through bearing 9' and is provided with the

usual means not shown for transmitting motion to a governor operating a steam inlet valve in pipe 23.

The casing 12 of the turbine and also its cover 10 are made in two parts horizontally. Casing 12 and casing 12' may have flanges for bolting the said casings together in case it is desired to have the casings in separate castings. The wall 24 of casing 12' may 10 also be a cover and connected to the shell of casing 12' which then has a flange.

In case of two or more impulse stages being used, a diaphragm is placed between the stages.

15 It will be seen that my invention represents a compact construction that is simple and strong avoiding expensive drums and all sorts of labyrinth packing and is self balancing.

20 Various changes may be made without deviating from the spirit of my invention.

Having thus described my invention, I claim:—

1. A steam turbine having a high pressure working wheel provided with a series 25 of radial disposed blading, and having a low pressure working wheel with axially disposed blading, and a series of intermediate pressure blading carried by said high pressure working wheel, a casing for each of said 30 wheels and blades in said casings coöperating with the blading in said wheels, an inlet and an outlet for the turbine.

2. A steam turbine having a high pressure working wheel provided with a series 35 of radial extending blading and also provided with a series of axially extending blading and a low pressure working wheel having axially disposed blading, all as set forth.

3. A steam turbine having a high pressure working wheel provided with a series 45 of radial extending blading and also provided with a series of axially extending blading, and a low pressure working wheel having axially disposed blading and stationary blading fixed in the walls of the turbine co-acting with the said blading carried by the said working wheels.

50 4. A prime mover, provided with a primary wheel having impulse driving elements on its periphery and having reaction driving elements on its side, a casing for said wheel, means in said casing coöperating with the said driving elements on the wheel, a non-conducting element in said casing, a cover for said non-conducting element, and means for securing said element and the cover therefor to the casing.

55 60 5. A prime mover provided with a primary wheel having driving elements on its periphery and having driving elements on its side, a casing for said wheel, means in said casing coöperating with the said driving elements on the wheel, a secondary wheel

having driving elements on each side thereof, a casing for said wheel, means in said casing coöperating with said driving element on the secondary wheel, an inlet to the primary wheel, an outlet from said primary wheel leading to the secondary wheel and an auxiliary inlet to said secondary wheel and an exhaust outlet. 70

6. A prime mover provided with a primary wheel having impulse driving elements on its periphery and having reaction driving elements on its side, a casing for said wheel, elements in said casing coöperating with the said driving elements on the wheel, a motive fluid inlet for the casing, and an insulation secured to said casing, said insulation being axially opposite the inlet of the casing as shown and for the purpose set forth. 75

7. A steam turbine, comprising a casing 85 having a wall provided with an inlet, and a wall provided with an outlet and a series of blades extending inwardly, and also provided with an inclosing wall having a series of blades extending inwardly, a wheel 90 in said casing having blades coöperating with the blades in the said side wall and in the said inclosing wall, all as shown and as set forth.

8. A steam turbine, comprising a casing 95 having a wall provided with an inlet, and a wall provided with an outlet and a series of blades extending inwardly, and also provided with an inclosing wall having a series of blades extending inwardly, a wheel in 100 said casing having blades coöperating with the blades in the said side wall and in the said inclosing wall, and a non-conducting means within said casing, opposite the inlet for said casing and a means for securing 105 said non-conductor in said casing, all as shown and set forth.

9. A steam turbine, comprising a casing, a working wheel within said casing, driving elements radially disposed on said wheel, 110 and driving members axially disposed on said wheel members in said casing coöperating with said driving members on the wheel, an insulation in said casing, an inlet, and an outlet for said casing. 115

10. A steam turbine, comprising a casing, a working wheel within said casing, driving elements radially disposed on said wheel, and driving members axially disposed on said wheel members in said casing coöperating with said driving members on the wheel, an insulation in said casing, an inlet, and an outlet for said casing, a second casing, a wheel in said casing, opposite axially extending blading in said wheel, blading in 120 said casing, coöperating with said blading in the wheel, inlets to said blading, an auxiliary inlet to said blading, and an exhaust outlet to the atmosphere or to a condenser. 125

11. A steam turbine, comprising a shaft. 130

wheels mounted on said shaft, a separator between said wheels on said shaft, a casing inclosing each of said wheels, an inlet to one of said wheels, and inlets for the other of said wheels, an outlet for the last named wheel, driving members on the wheels and coöperating members in the casing for said wheels, and a non-conducting means in one of said casings opposite the inlet therefor 10 and for the driving members of the wheel.

12. A steam turbine having an impulse wheel, a casing therefor, reaction blades on said impulse wheel, stationary blades on one side of one wall of said casing coöperating with the said reaction blading on the 15

impulse wheel, a wheel having opposite extending reaction blades, a casing for said wheel, the walls of said casing having blades coöperating with the reaction blades on the said wheel, a passage in said wheel and a 20 passage in one of said walls, and a communicating passage for said casings, and an exit from said casing.

In testimony whereof I affix my signature in presence of two witnesses.

SOREN C. ROCKMAN.
